PRESSURE APPLYING PADS

Norman Victor Germany, Leicester, England, assignor to United Shoe Machinery Corporation, Flemington, N. J., a corporation of New Jersey

Application September 12, 1956, Serial No. 609,386

Claims priority, application Great Britain
October 7, 1955

4 Claims. (Cl. 12—38)

This invention relates to shoe bottom pressing pads for use in cement sole attaching presses, and more particularly to an improved pad of the type disclosed in United States Letters Patent No. 2,205,400, granted June 25, 1940, upon an application filed in the name of Sidney J. Finn.

The pad of the aforementioned patent comprises a solid rubber forepart portion, a solid rubber heel portion, and an intermediate or shank portion made up of a plurality of rubber sections extending transversely and longitudinally of the pad, each section being housed in a metal casing resting against the top of a rubber water bag supported on the bottom of a pad box, whereby the pad sections, in response to pressure of a shoe in the cement sole attaching operation, may move relatively to each other bodily heightwise of the pad and also about axes extending lengthwise of the pad to enable them to accommodate themselves to the curvature of the shank portion of the shoe bottom.

It is an object of the present invention to provide an improved pad of the type above referred to, whereby the sectional shank portion of the pad may be made even more effective than heretofore in operating upon the rounded shank portion of women's shoes, to enable the pad to exert uniform pressure against all portions of the bottom of the shoe.

To this end, and in accordance with a feature of the invention, there is provided a pressure applying pad comprising a forepart portion and a heel end portion, each formed of a solid but resilient block of rubber, and a shank portion consisting of a plurality of rubber sections. As herein illustrated, each section comprises two members pivotally mounted between two metal strips, whereby not only may the pair of members of each section move, as heretofore, bodily as a unit heightwise of the pad, but each member may pivot individually about an axis extending lengthwise of the pad, thus enabling the shank sections of the pad to conform closely to the curvature of the shank portion of the shoe bottom and to press the marginal portions of a sole against the bottom of a shoe with uniform pressure, even though the shoe may be slightly misplaced on the pad.

In the drawings,

Fig. 1 is a side elevation, partly broken away and partly in section, illustrating the novel pad provided by the invention installed on a pad box and supporting a sole and a shoe to which the sole is to be attached;

Fig. 2 is a view in front elevation of one of the sections constituting the shank portion of the pad; and

Fig. 3 is a section along line III—III of Fig. 2.

The illustrated pressure pad is particularly adapted for use in a pad box of the type disclosed in United States Letters Patent No. 2,568,065, granted September 18, 1951, upon an application filed in the name of Helge Gulbrandsen. This box comprises angularly adjustable bottom parts 10, 12 and 14 which support an under pad, which may be a relatively soft rubber water bag, as in the pre-

2

viously mentioned Gulbrandsen patent. In the illustrated embodiment of the invention the under pad consists of a series of layers 16 of low durometer rubber, substantially as disclosed in an application for United States Letters Patent, Serial No. 519,125, filed June 30, 1955 now Patent No. 2,810,142, granted October 22, 1957 in the name of Helge Gulbrandsen.

Resting on the top layer of the under pad is an upper pad of the type disclosed in the above-mentioned Finn Patent and comprising a solid rubber forepart portion 18, a solid rubber heel portion 20, and an intermediate or shank portion which, as in the aforementioned Finn patent, consists of a plurality of rubber sections 22, each section comprising a pair of members 24, 24 (Fig. 2). In contrast, however, to the arrangement in the Finn patent, where the pair of members comprising a section is housed in a metal casing resting on top of the under pad, in the pad of the present invention each member of a pair is pivotally mounted between two metal strips 26, 26 so that each member can, by swinging about its pivot, accommodate itself individually to the portion of the sole on which it operates.

For this purpose each rubber member 24 has its lower portion reduced on each side at 28 by an amount slightly less than the thickness of the metal strips. Each rubber member has provided at approximately the center of its reduced portion a hole 30 which is of such a diameter as to allow free rotary movement of the member on the center portion of a pin 32. The length of the center portion of the pin is slightly greater than the thickness of the lower portion of the rubber members. Extending axially in opposite directions from the center portion of the pin are short stems 34, 34, of less diameter than the center portion, so as to provide shoulders on the pin against which the strips, which are provided with two holes of the same diameter as the stems, may be located and fixed by riveting over and filing flush the ends of the stems. The rubber members 24, 24 are thus confined between the pair of strips 26, 26, but are free to pivot on the pins 32. Moreover, a gap is left between the two rubber members of each section so as not to restrict the pivotal movement of the members. The arrangement of the strips in the assembly just described is such that a slight space is provided between the rubber members of one section and those of the adjacent sections to prevent frictional engagement between the members of the various sections. As indicated at 36 in Fig. 2, the lower edge of each rubber member 24 may be cut away at a slight angle on each side of the hole to enable the member to rock freely on the under pad.

It will thus be appreciated that when a number of these sections having suitable upper contours are placed side by side to form the intermediate portion of the pad and the pad is pressed against a shoe bottom, not only is each section able to rock upon or sink into the under pad, but each rubber member is able to pivot individually about its pin to accommodate itself closely to the curvature of the shank portion of the sole, thereby to insure that the marginal portions of the sole are firmly pressed against the shoe bottom to cause them to adhere together right to the feather, which is essential. The provision for pivotal movement of each rubber section also allows the sections to accommodate themselves accurately, even though the shoe may be slightly misplaced on the pad.

Having thus described my invention, what I claim as new and desire to secure by Letters Patent of the United States is:

1. In an apparatus for use in applying pressure to shoe bottoms having an underpad, a pressure pad overlying the underpad comprising a single resilient forepart portion, a single resilient heel portion, and a shank portion con-

sisting of a plurality of resilient, transversely extending sections, each section comprising a pair of members, and means mounting the pair of members of each section for movement together as a unit relatively to the other sections heightwise of the underpad and also for pivotal movement individually about an axis extending lengthwise of said underpad.

2. A pad for applying pressure to shoe bottoms comprising a forepart portion, a heel portion and a shank portion, said shank portion being divided into a plurality of transversely extending sections, each section comprising a pair of pressure applying members, a metal strip extending lengthwise of each section at either side thereof, and means pivotally connecting each member of a section to said metal strips, whereby the two members of each section are confined between two metal strips to move as a unit and each member is capable of pivoting independently in accordance with variations in the curvature of the shank portion of a shoe.

3. A pad for applying pressure to shoe bottoms comprising a forepart portion, a heel portion and a shank portion, said shank portion being divided into a plurality of transversely extending sections, each section comprising a pair of pressure applying members each having a

5 lower reduced portion, metal strips extending lengthwise of the lower reduced portions of the pair of members of each section at opposite sides thereof, said lower portions of the members being reduced by an amount less than the thickness of the metal strips.

4. In an apparatus for use in applying pressure to shoe bottoms having an underpad, a pressure pad overlying the underpad comprising a single resilient forepart portion, a single resilient heel portion, and a shank portion, said shank portion consisting of a plurality of resilient, transversely extending sections, each section comprising a pair of members, and means mounting the pair of members of each section for movement together as a unit relatively to the other sections heightwise of the underpad and also for 15 pivotal movement individually about an axis extending lengthwise of said underpad, the lower edge of each member of a section being shaped so as to facilitate the rocking movement of the member on the underpad.
